DANIEL KOPS, OF NEW YORK, N. Y.

APPAREL-CORSET.

1,135,698.

Specification of Letters Patent. Patented Apr. 13, 1915.

Application filed June 6, 1914. Serial No. 843,323.

To all whom it may concern:

Be it known that I, DANIEL KOPS, a citizen of the United States, residing in the borough of Manhattan, city, county, and 5 State of New York, have invented an Improvement in Apparel-Corsets, of which the following is a specification.

In Letters Patent, No. 1,082,273, granted to me December 23, 1913, for an apparel corset, I have shown and described a corset structure in which each corset body half is provided with a depending skirt member extending from a rear edge thereof forwardly, and a front skirt extension completing the continuity of the skirt to approximately the front medial line of the corset body half, and secured at one side edge to the skirt and a portion of the corset body half, and along the top edge to the front 10 portion of the corset body half, the object of this structure being to provide a corset by which the usual advantages of the skirt members are obtained and at the same time one in which the straight front effect is produced, and a proper support provided for the lower portion of the abdomen of the wearer. It is to be noted in this case, however, that the front skirt extension members are fixed and consequently are in nowise adjustable to position relatively to the front 15 body portion of the corset.

In Letters Patent No. 1,105,330, granted to me July 28, 1914, I have shown and described a corset structure similar to that to which reference has hereinbefore been made, with the exception that the front skirt extension members are not attached at their upper edges to the lower front portions of the corset body halves, and that hook and 20 eye members, or other similar means, are employed for adjustably attaching the upper front portions of these front skirt sections to the lower front portions of the corset body halves, in order that the relationship between these members may be adjustable. In 25 this structure, however, it has been found that the entire strain, both longitudinally of the corset, due to the tension of the hose supporters attached to the lower edges of the front skirt extensions, and transversely of the corset, depending upon the tightness with which the garment fits, have been placed upon the hooks and eyes, or other similar devices employed for attaching the

upper front portions of the skirt extensions 55 to the lower front portions of the corset body halves, as aforesaid. The tendency, therefore, is to cause the hooks to break or the eyelets to wear out, or to otherwise impair these members, or similar devices which 60 may be employed for this purpose.

The object of my present invention, therefore, is to overcome this difficulty, and in doing so, I provide a corset structure similar to those hereinbefore described, with the inclusion of a tension strap or other similar device designed to relieve the longitudinal strain placed upon the devices for adjustably attaching the front skirt sections to the corset body halves, so that the principal 65 strain placed upon these attaching devices is merely the lateral or transverse strain.

The use of this garment has also demonstrated the fact that the tension strap or other similar device employed not only perform the function hereinbefore stated but also has a tendency of forcing the lower front portion of the corset against the body of the wearer, thereby insuring the necessary abdominal support and at the same time 75 forces upwardly the upper portion of the corset body halves immediately below the bust line, so as to relieve the pressure which would otherwise be placed upon the body of the wearer along this line. 85

The construction of this corset will be hereinafter more particularly described.

In the drawing, Figure 1 is a front elevation of an apparel corset in which my present improvement is embodied. Fig. 2 is an 90 enlarged elevation of the lower front portion of the corset, one of the skirt extensions being broken away in order the more clearly to illustrate the tension strap employed, and Fig. 3 is a longitudinal cross section illustrating the parts of the corset comprising 95 my present invention.

Referring to the drawing, in carrying out my invention, and as usual, the corset comprises corset body halves 10 and 11, which, 100 along the front edges, are provided with suitable clasps 12, by which the corset body halves, at the front, are joined and series of eyelets 13 along the rear edges, through which laces 14 are threaded for connecting 105 the corset body halves at the rear.

The corset body half 10 is provided with a skirt 15, and the corset body half 11 with

the skirt 16. These skirt members extend downwardly from the corset body halves, as is usual, and also from the rear medial lines thereof forwardly. The skirt member 15 is 5 provided with a skirt extension 17, and the skirt member 16 with an extension 18. The skirt extension 17 is connected along one side edge to the forward edge of the skirt 15, and also to a portion of the corresponding 10 corset body half 10, as indicated by the line of sewing 19. The upper edge 21, of this skirt extension 17, however, is unattached to the corset body half. Similarly, the skirt extension 18, along one side edge thereof, is 15 connected to the front edge of the skirt 16, and also to a portion of the corset body half, as is indicated by the line of sewing 20, and the upper edge 22 of the skirt extension 19, similarly to the upper edge 21 of the skirt 20 extension 17, is not attached to its corset body half.

Each skirt extension is provided in suitable positions, in the upper forward portion thereof, with eyelets 23, and the corset steels 25 adjacent the lower portions thereof are fitted with hooks 24, adapted to engage either of the eyelets 23 in order that the skirt extensions may be adjustably connected to the corset body halves in the same 30 manner as described in my co-pending application aforesaid. In the structure, as hereinbefore described, however, and as is also hereinbefore mentioned, the entire strain, both longitudinally of the corset and transversely thereof, is placed upon the said hook and eye members. In order to overcome this difficulty, I now employ in each corset body half, a tension strap made of any suitable inelastic material.

40 As clearly shown in Fig. 2, the tension strap 25 associated with the corset body half 10, and the skirt extension 17, is attached at its upper end to the lower portion of the corset body half along a line substantially 45 parallel to the upper front edge of the skirt extension. These lines of attachment being indicated at 26. At its lower end, this tension strap is connected to the lower edge of the skirt extension 17, adjacent the corner thereof, the lines of attachment being indicated by 27. At this point, also, and if desirable, by the same lines of sewing a hose supporter or similar attaching device 28, may be secured to the skirt extension 17. 50 The other corset body half is similarly provided with a tension strap 29, secured at its upper end to the lower portion of a corset body along the lines of sewing 30, and at its lower end to the lower edge of the skirt extension 18 at the corner thereof, as indicated by the lines of sewing 31, at which points, also, a hose supporter 32, or other tension device is attached to the skirt extension. Also, as shown in the drawing, 60 the skirt members, in suitable positions, may 65

have other hose supporters or tension devices 33, attached to and extending from the lower edges thereof.

In the use of the garment hereinbefore described, the tension placed upon the skirt members longitudinally thereof by the hose supporters 28 and 32, is placed largely upon the tension straps 25 and 29, relieving the skirt sections 17 and 18 of this lateral strain, and correspondingly removing the strain 75 from the hook and eye members, only sufficient longitudinal pull being placed on the front skirt extensions to maintain the same 70 in their proper positions for use.

As will readily be understood, the hook 80 and eye members are therefore only depended upon to withstand the lateral or transverse strain placed upon the same by the fit of the garment to the body of the wearer. It will also be apparent that the 85 pulling of the straps 25 and 29 by the tension placed upon the same, will force the lower front portions of the corset body inwardly to more securely support the abdomen of the wearer and at the same time 90 force outwardly the upper portions of the corset body halves immediately below the bust line, so as to relieve the pressure against the body of the wearer, which will otherwise be placed upon the same along this 95 line.

I claim as my invention:

1. An apparel corset comprising a corset body half, a skirt attached to each corset body half, extending forwardly from the 100 rear medial line thereof, a skirt extension member completing the continuity of each skirt to substantially the front medial line of the corset and connected along one side edge to its skirt and a portion of the corset 105 body half, and at its upper edge free from the corset body half, devices for adjustably attaching the upper front portion of the skirt extension to the lower front portion of the corset body half, a hose supporter by 110 which, in use of the garment, a longitudinal tension is placed upon the skirt extension and the attaching device, and means for relieving the longitudinal tension placed on the said attaching device, and simultaneously forcing inwardly the lower front portion of the corset body half and forcing outwardly the upper front portion of the corset 115 body half at the bust line.

2. An apparel corset comprising corset body halves, a skirt attached to each corset body half, extending forwardly from the rear medial line thereof, a skirt extension member completing the continuity of each skirt to substantially the front medial line 120 of the corset and connected along one side edge to its skirt and a portion of the corset body half, and at its upper edge free from the corset body half, devices for adjustably attaching the upper front portion of the 125

130

skirt extension to the lower front portion of the corset body half, a hose supporter attached to the lower edge of the skirt extension adjacent the corner thereof, and a tension strap fixed at its upper end to the lower portion of the corresponding corset body half, adjacent the line of the free upper edge of the skirt extension and at its

lower end to the lower edge of the skirt extension adjacent the front corner thereof. 10

Signed by me this 1 day of June, 1914.

DANIEL KOPS.
